UNITED STATES PATENT OFFICE

JAMES M. FAGAN, OF MAPLEWOOD, NEW JERSEY, ASSIGNOR TO WESTINGHOUSE LAMP COMPANY, A CORPORATION OF PENNSYLVANIA

METHOD OF MAKING MERCURY SWITCHES

Application filed August 27, 1930. Serial No. 478,022.

This invention relates to mercury switch devices and relates more particularly to a method of evacuating and providing such devices with a mercury pool.

5 An object of the invention is to provide a simple and convenient method of introducing a definite amount of mercury into a container.

10 Another object of the invention is to provide a method of supplying a bulb with mercury and evacuating without removal of the mercury.

15 Another object of the invention is to provide a progressive method of evacuating a bulb, introducing an excessive quantity of mercury therein, removing a portion of the mercury and filling the bulb with a gaseous environment.

20 Other objects and advantages of the invention will be more fully understood from the following description together with the accompanying drawing, in which

25 Fig. 1 shows a mercury switch device partly in section in loading position on a conveyor for movement for an exhausting operation;

Fig. 2 shows a bulb in position for exhausting;

30 Fig. 3 shows the bulb partly in section and in position to receive a quantity of mercury;

Fig. 4 shows the bulb in position for the removal of a portion of the mercury;

35 Fig. 5 shows the bulb in position to receive a gas filling, and

Fig. 6 shows the bulb in position for a sealing or tipping off operation.

The present invention is practiced for supplying mercury to a mercury switch of the 40 type disclosed in co-pending application Serial No. 477,521 filed August 25, 1930, assigned to the same assignee as is the present application.

45 As shown in Fig. 1 the bulb employed in practicing the present invention may comprise a glass envelope 10 comprising a press 11 in which is sealed a pair of electrodes 12 and 13. The press 11 is provided with a passageway 14 communicating with an external 50 exhaust tube 15 and with a tubular exten-

sion or stand-pipe 16 which latter extends into the bulb or envelope a predetermined distance.

55 Mounted on the electrodes 12 and 13 is a refractory element 17 having a cavity 18 in which an end of the electrode 13 is disposed. Leading from the cavity is an inclined surface 19 and the electrode 12 extends into the refractory element at substantially the lower end of the said inclined surface. 60

65 A mercury switch constructed as above described is provided with a mercury pool and when the switch is in operation it is tilted so that the pool of mercury moves to make connection between the electrodes or to break the connection between the electrodes. It is essential in devices of the present character to provide a definite amount of mercury in each device. Furthermore it has been found difficult to introduce a quantity of mercury 70 and evacuate the device without drawing out a part of the mercury into the vacuum line. 75

When evacuating the bulb in accordance with the present invention and filling the same with mercury the exhaust tube 15 is inserted into an exhaust rubber 21 of a conveyor 22 of an exhaust machine. The exhaust rubber 21 is connected by means of a tubular conductor 23 with the valve of a vacuum pump (not shown). 80

85 Any suitable conveyor type vacuum machine may be used in which a plurality of exhaust ports 24 are employed and which during a movement of the conveyor are successively connected with vacuum pumps for evacuating a hollow vessel as for example an exhaust conveyor such as that shown in Patent 1,596,733 issued August 17, 1926, may be used.

90 After the device is inserted in the exhaust rubber as shown in Fig. 1 it is moved into what may be termed an evacuating position indicated in Fig. 2. In this position the vacuum pump removes the gas from the tube and the conveyor then moves the device until the conductor 23 is connected with a mercury supply line 25 which leads from a mercury supply tank 26. A valve 27 is provided and a given amount of mercury 28 is permitted 95 to flow into the bulb. As shown the amount 100

of mercury may be in such quantity as to have a depth greater than the height of the tubular extension 16. The conveyor may then be moved to connect the conductor 23 with a tank 29 for receiving surplus mercury. The tank may be connected with a vacuum line 30 and the mercury in the bulb 10 above the level or outlet orifice 31 of the extension 16 will be drawn out leaving a mercury pool 32 with its surface substantially flush with the inner end of the extension 16 thus determining the level of the pool 32.

After the mercury pool 32 has been introduced the device may again be evacuated to remove mercury vapors and the conductor 23 may be connected with a suitable gas line to admit a gaseous filling as for example hydrogen. The conveyor may then move the device to a position as shown in Fig. 6 where in the exhaust tube 15 is disposed between fires 33 and 34 which perform a tipping off operation. At this position jaws 35 and 36 may engage the bulb and as the fires tip off the same the bulb may be removed from the conveyor.

The above method may be practiced for supplying a mercury pool of a definite amount to a device by removing excess mercury. It will be understood, however, that by reason of the tubular extension 16 the bulb may be moved to position as for example Fig. 3 and a definite amount of mercury may be admitted to the device, such amount being so controlled that its depth when in the device will be of a dimension less than the height of the tubular extension. A device so filled may be readily evacuated by an exhaust pump without causing any mercury to flow into the exhaust line since the outlet orifice at the upper end of the tubular extension is above the mercury level a vacuum may be produced in the device without sucking or drawing any of the mercury through the exhaust tube.

The present invention affords a simple and effective method of exhausting and supplying a mercury switch with a mercury pool and simplifies manufacture as well as reduces operating costs since by reason of the projecting tubular extension a definite amount of mercury may be introduced into the device by the above described method and the danger of clogging the exhaust valves with mercury removed from the device is avoided.

Although a preferred embodiment of the invention is shown and described herein it is to be understood that modifications may be made therein without departing from the spirit and scope of the invention as set forth in the appended claims.

What is claimed is:

1. The method of filling a mercury switch device which comprises providing a bulb with an exhaust tube extending a given dis-

tance therein, evacuating said bulb through said tube, connecting said tube with a mercury supply line, admitting a quantity of mercury to a depth above the outlet orifice of the tube and causing the mercury to flow out through said tube so that the surface of the remaining mercury pool is level with the edge of the extended exhaust tube.

2. The method of manufacturing mercury switches which comprises, providing a bulb with an exhaust tube extending into the bulb a distance equal to the depth of the amount of mercury required, supporting the bulb with the inner end of the exhaust tube uppermost, evacuating the bulb through the exhaust tube, introducing mercury into said bulb to a level above the upper end of the exhaust tube and causing the portion of mercury above said end to flow out of said bulb through said tube while the bulb is supported as above mentioned, so that the length of the extended portion of said exhaust tube will limit the depth of the mercury.

In testimony whereof, I have hereunto subscribed my name this 22nd day of August, 1930.

JAMES M. FAGAN.
